US0D1079644S

(12) **United States Design Patent** (10) **Patent No.:** **US D1,079,644 S**
(45) **Date of Patent:** **** Jun. 17, 2025**

(54) **MEDICAL DEVICE CONNECTOR**

(71) Applicant: **Physio-Control, Inc.**, Redmond, WA (US)

(72) Inventors: **Christopher Alviar**, Seattle, WA (US); **Ryan Bowman**, Richland, WA (US); **Cathlene Buchanan**, Shoreline, WA (US); **Kristina Edmonson**, Woodinville, WA (US); **Brendan Greetham**, Redmond, WA (US); **Jeremy Wong**, Redmond, WA (US); **Nikolaos Kalogeropoulos**, Redmond, WA (US); **Christian Schneider**, Redmond, WA (US)

(73) Assignee: **Physio-Control, Inc.**, Redmond, WA (US)

(**) Term: **15 Years**

(21) Appl. No.: **29/914,003**

(22) Filed: **Oct. 11, 2023**

Related U.S. Application Data

(63) Continuation of application No. 29/798,555, filed on Jul. 8, 2021, now Pat. No. Des. 1,007,426, which is a (Continued)

(57) **CLAIM**

The ornamental design for a medical device connector, as shown and described.

DESCRIPTION

FIG. 1 is a top, front, right-side perspective view of a medical device connector;
FIG. 2 is a right-side view thereof;
FIG. 3 is a left-side view thereof;
FIG. 4 is a top view thereof;
FIG. 5 is a bottom view thereof; and,
FIG. 6 is a front view thereof.
The dashed broken lines depict portions of the medical device connector that form no part of the claimed design.
